ABSORBER TYPE REFRIGERATING SYSTEM
WITH BOILER FEED

Kemper P. Brace, Brooklyn, N. Y.

Application May 23, 1935, Serial No. 23,097

8 Claims. (Cl. 62—119)

This invention relates to refrigerating systems of the absorber type. Its object is to provide a new and simple method of causing circulation of the absorbing liquid from the absorber to the generator or boiler with a minimum of simple moving parts, and without the use of an inert gas or vapor to balance pressures between the absorber and the generator.

Further objects and advantages will become apparent from a study of the description and the drawings.

Referring to the accompanying drawings which are made a part hereof and on which like numerals refer to the same part throughout,

Figure 1 is a view in elevation of one form of the system, and,

Figure 2 is a similar view of a modification of the system.

Referring to Figure 1, numerals 1, 2 and 3 denote the evaporator, the absorber and the generator or boiler, respectively, of an absorber type refrigerating system. The boiler is partially filled with a suitable solution 4 from which refrigerant is boiled off by means of another fluid at a higher temperature than the solution 4, as will later be described. The refrigerant used may be ammonia (NH_3) and the solution 4 may be a solution of ammonium thiocyanate (NH_4CHS) in ammonia. Ammonia vapors boiled off the solution 4 pass thru pipe 5 to a condenser 7 where they are liquefied and pass to receiver 8. A float controlled valve 9 controls passage of liquid from the receiver to the evaporator and prevents the passage of gas from the receiver to the evaporator in the event that there should be no liquid in the receiver. Heat is extracted from the media being refrigerated which may surround the evaporator, this heat passing into the refrigerant and causing evaporation of some of the refrigerant. The evaporated refrigerant passes thru a pipe 10 into the solution 11 in the absorber. The solution in the absorber is cooled by a cooler 12, which as here shown may be an air cooler or may be any other suitable cooler. Solution is returned from the absorber 2 to the boiler thru pipe 13, check valve 14, pipe 15, check valve 16 and pipe 17. Solution is supplied from the boiler to the absorber thru float controlled valve 18, heat exchanger 19 and pipe 20.

The pressure in the boiler is greater than the pressure in the absorber. In order to have a flow of the solution from the absorber to the boiler systems of this general character heretofore have used an inert gas such as hydrogen to balance the pressure difference between the ab-

sorber and the generator. My system avoids the use of such a gas and provides means for effecting the return of the solution from the absorber to the boiler, which means will now be described, in connection with the means for heating the boiler 3 with which it is connected.

An auxiliary boiler 21 contains a solution or liquid 22 which boils at a temperature much higher than the boiling temperature of the solution 4. Suitable examples of such liquids are diphenyl, mercury, benzol chloride, benzyl benzoate, glycerine, and various oils, etc. The boiler is heated by a suitable heater 23. A pipe 25 conducts the vapor 24 which is boiled off the liquid 22 to a chamber 26 which surrounds a portion of the boiler 3 or which is arranged at least so that the vapors 24 are brought into heat exchange relation with the boiler 3. The boiler 3 being cooler than the boiling point of the liquid 22 will condense the vapor 24, the liquid resulting therefrom falling into a well 27. Heat extracted from the vapors 24 and hot liquid condensed will pass into the solution 4 and effect vaporization of some of this solution, driving off refrigerant, which as stated, may be ammonia. A tube 28 siphons hot liquid from the well 27 and delivers it into chambers 29 and 30 from which it flows thru pipe 31 back to the boiler. The pipe 31 has a restricted portion 32 to retard the flow of liquid from the chambers 29 and 30, for a purpose which will presently appear.

A tube 33 is connected at its upper end with the pipe 15 and extends down into the chamber 29. The tube has on its lower end a bulb 34 having fins 35, the fins providing better heat exchange between the liquid in the chamber 29 and the solution in the bulb 34, which solution, as is apparent, is the same as that in the absorber. A liquid trap 36 in the tube 28 prevents passage of any vapor to the chambers 29 and 30.

Operation of the system is as follows: Heat is applied to the boiler 21 to boil off vapor 24 from the liquid 22. This vapor passing into the chamber 26 contacts the boiler 3 and boils the solution 4 therein. The boiling point of the solution 4 being lower than the boiling point of the liquid 22, vapors 24 are condensed and collect in the well 27. The hot liquid collecting in the well is still hotter than the boiling point of the solution 4. This hot liquid is siphoned into chambers 29 and 30, and due to the restriction 32 is held in the chambers 29 and 30 for some appreciable time. This heats the solution in the bulb 34 and vaporizes some of it. The resulting pressure forces solution thru pipe 15, check valve 16 and pipe 17 into boiler 3.

The check valve 14 prevents the solution from returning to the absorber. As soon as all the liquid in chambers 29 and 30 has drained into the boiler 21, air will pass down thru chamber 30 and up thru chamber 29 cooling the bulb 34. This will condense the vapors in the bulb 34, reducing the pressure therein to draw solution thru check valve 14 from the absorber, check valve 16 preventing solution from returning from the boiler. 10 In this way solution will be pumped from the absorber to the boiler. While the bulb 34 was filling with solution from the absorber, the well 27 was again filling with liquid condensed by the boiler 3 to start the cycle over again. 15 It is possible that some trouble may be caused by crystallization of NH₄CH₃S in bulb 34 due to the fact the fresh solution from the absorber may not diffuse and mix rapidly in the bulb. To avoid difficulties of this kind I have provided a modified form of the invention which is shown in Figure 2.

The upper portion of Figure 2 is the same as that shown in Figure 1 and indicates an absorber refrigerating system of conventional construction. Boiler 40 is heated by vapors boiled off the liquid in the boiler 41 by heater 42. Liquid resulting from contact of the vapors with the walls of the boiler 40 will collect in well 43 and flow thru siphon tube 44 to the U-shaped chamber 45 and out of this chamber thru tube 46 back into the boiler 41. The tube 46 has a restriction 47 to retard flow of the hot liquid from the chamber 45 to the boiler. A second U-shaped chamber 49 is partially filled with a liquid different from the solution in the boiler and absorber. A metal element 52 carries a cup 53 positioned within the closed end of the U-shaped member 49. The metal element extends into the U-shaped chamber 45 and has fins 54 to effect better heat transfer between the liquid in the chamber and the metal element.

Operation is as follows: hot liquid returning from the well 43 is held in the chamber 45 long enough for the heat from the liquid to be transmitted thru the metal element 52 to the cup 53. 45 Some vapor will be generated above the liquid 48 to create a pressure which will act thru the column of liquid to force a portion of the solution from the absorber thru the check valve 51 into the boiler 40. When all of the liquid has 50 drained out of the chamber 45 air will flow thru the chamber and out thru the upper end, and coming in contact with the end of the element 52 will cool this element and consequently condense the vapor above the liquid 48. Reduction 55 of pressure resulting, solution will be drawn from the absorber thru check valve 50, check valve 51 preventing return of solution from the boiler.

For efficient operation the amount of liquid in bulb 34 in Figure 1 and in cup 53 in Figure 2 should be small, so that a large amount of liquid will not have to be heated and cooled. It will be apparent that the liquid in the cup 53 and in the tube 34 will be alternately heated to its boiling point and cooled to the condensing point. The boiling point will be slightly higher than the boiling point in the refrigerant boiler and the condensing point will be approximately equal to the temperature maintained in the absorber. 65 Since quite a high temperature difference exists between the absorber and the generator it is obviously advantageous to keep the amount of liquid in cup 53 and bulb 34 as small as possible to reduce heat losses due to alternate heating 70 and cooling as it is only the actual vaporization

of the liquids in 53 and 34 that pumps solution from the absorber to the boiler. The ideal set up would be to have cup 53 or bulb 34 hold only that amount of liquid which when entirely vaporized would force the required quantity of weak 5 solution into the boiler at each siphoning of hot liquid from the well.

For controlling the temperature at the evaporator for faster freezing, etc., the simplest and most efficient way is to design the whole machine 10 large enough to take care of the lowest temperature in the evaporator under the worst conditions and apply a high and low control of the flame under the boiler. This corresponds to the on and off control common with domestic and 15 commercial electric refrigerators. With this sort of control all other factors in the machine can be made constant and invariable which will greatly simplify the construction and reduce the cost of the machine. The operation of this control would be as follows: suppose the minimum temperature desired in the evaporator is 10 degrees and the heat load at this temperature is 300 B. t. u. per hour. Then the whole machine should be designed for say 400 B. t. u. per hour 20 at the above evaporator temperature and highest condenser temperature. A thermostat would then be set in the evaporator which would practically shut off the flame under the boiler when the temperature of 10 degrees is reached and turn it 25 on when a temperature of 12 degrees has been attained. Thus the machine would operate about three fourths of the time at substantially full capacity. If a temperature of 15 degrees is desired in the evaporator, the thermostat could be 30 set to practically shut off the flame at 15 degrees and turn it on at 17 degrees and of course at this setting the machine could still operate at its full capacity while running but would not run as much of the time as at the lower temperature. 40

It will be obvious to those skilled in the art that various changes may be made in the invention without departing from the spirit thereof, I, therefore, do not limit myself to the invention as shown in the drawings and described in the 45 specification but only as set forth in the appended claims.

What I claim is:

1. A refrigerating system of the absorber type comprising a boiler, a condenser, an evaporator, 50 an absorber, an auxiliary boiler, means for continuously driving off vapor from said auxiliary boiler to heat said first named boiler, means for condensing said vapor and returning it intermittently to said auxiliary boiler, and means for utilizing some of the heat energy in said returning fluid for effecting transfer of fluid from said absorber to said boiler.

2. In an absorber type of refrigerating system, a boiler, means for heating the boiler, an evaporator, and an absorber, means for transferring fluid from the absorber to the boiler comprising a fluid line from said absorber to said boiler having spaced apart check valves therein arranged to permit flow of fluid from the absorber to the boiler and prevent reverse flow and a pulsating column of liquid connected in said line between said check valves and means for effecting pulsations of said liquid, said last named means being operated by said boiler heating 65 means.

3. A refrigerating system comprising a boiler, a fluid heater for said boiler, an evaporator, an absorber, a supply line between said absorber and said boiler, check valves in said line to permit 70

- flow of fluid from said absorber to said boiler but to prevent reverse flow, a fluid connection to said supply line between said check valves, and fluid means operated by said fluid heater 5 for intermittently heating a portion of the fluid in said fluid connection for alternately increasing and decreasing pressure in said connection.
4. In an absorber type of refrigerator having a boiler and absorber, an auxiliary boiler for 10 heating said first named boiler by vapors driven therefrom, means for returning to the auxiliary boiler the fluid boiled off, a conduit for returning solution from said absorber to said first named boiler, said conduit having check valves therein 15 to limit flow in one direction only, a connection to said conduit between said valves, a bulb in said connection, said bulb being placed in the path of the fluid returning to the said auxiliary boiler whereby the fluid therein is heated to subject 20 the solution in said conduit to a pressure to force said solution into the said first named boiler.
5. A refrigerating system of the absorber type comprising a boiler, a condenser, an evaporator 25 and absorber and a liquid return line from the absorber to the boiler, an auxiliary boiler having a connection for conducting vapor boiled off from said auxiliary boiler into contact with the first named boiler to condense said vapor and heat 30 said boiler, a reservoir for collecting the condensate, a siphon for intermittently returning liquid from said reservoir to said auxiliary boiler, and means for utilizing heat extracted from said returning liquid for forcing liquid thru said liquid return line from the absorber to the first 35 named boiler.
6. A refrigerating system of the absorber type comprising a boiler, a condenser, an evaporator
- and absorber, a liquid return line from the absorber to the boiler, an auxiliary boiler, means for heating said first named boiler by vapors boiled off from said auxiliary boiler, a pump having a reciprocating liquid piston, said pump having its suction and discharge communicating with said liquid return line, and means operated by said auxiliary boiler for reciprocating said piston. 5
7. A refrigerating system of the absorber type 10 comprising a boiler, a condenser, an evaporator and absorber, a liquid return line from the absorber to the boiler, an auxiliary boiler, means for boiling off vapor from said auxiliary boiler and bringing it into contact with the first named 15 boiler to heat said first named boiler, a line for returning liquid condensed from said vapor to the auxiliary boiler, a reservoir in said last named line, a restriction in said last named line intermediate the auxiliary boiler and said reservoir to 20 hold liquid in said reservoir for a predetermined time, a liquid piston pump communicating with the liquid return line, and means operated by heat extracted from the fluid returning to the auxiliary boiler for operating said piston to force 25 liquid from the absorber to the boiler.
8. In an absorber type of refrigerator, a boiler, means for heating said boiler, an evaporator, an absorber, a conduit for the return of liquid from said absorber to said boiler and means 30 for effecting the flow of liquid through said conduit comprising a pulsating column of liquid for intermittently transferring energy to the liquid in said conduit and means for utilizing said boiler heating means for effecting pulsation of 35 said column of liquid.

KEMPER, P. BRACE.
